MULTIPLE BUCK LAUNDRY PRESS

Frank Breckenridge, Mansfield, Ohio, assignor to
Westinghouse Electric Corporation, East Pitts-
burgh, Pa., a corporation of Pennsylvania

Application April 10, 1944, Serial No. 530,359

2 Claims. (Cl. 38—24)

1

My invention relates to laundry presses and has for an object to provide improved apparatus of this kind.

A further object of the invention is to provide an improved presser having a motor-driven mechanism for mechanically engaging and disengaging the heated shoe and the buck, said mechanism providing for the swinging of the shoe out of registry with the buck in order to enable the operator to arrange the fabrics to be pressed upon the buck.

A further object of the invention is to provide an improved domestic presser having a plurality of bucks of different configuration which are selectively operated to facilitate the pressing of flatwork and various forms of garments.

These and other objects are effected by my invention as will be apparent from the following description and claims taken in connection with the accompanying drawings, forming a part of this application, in which:

Fig. 1 is a front view partly in elevation and partly in section of a domestic presser constructed and arranged in accordance with my invention;

Fig. 2 is a side view partly in section and partly in elevation looking from the plane II—II in Fig. 1;

Fig. 3 is a view in elevation of a detail viewed from the plane III—III of Fig. 1;

Fig. 4 is a side view of the shoe actuating mechanism shown in Fig. 2 with parts broken away for the sake of clearness;

Fig. 5 is a sectional view taken along the line V—V of Fig. 4;

Fig. 6 is a sectional view taken along the line VI—VI of Fig. 4;

Fig. 7 is a view of a detail shown in Figs. 4 to 6, inclusive; and

Fig. 8 is a section taken along the line VIII—VIII of Fig. 7.

Reference will now be had to the drawings wherein I have elected to show my invention applied to a domestic presser including a frame structure, generally indicated at 10, and including spaced upright end members 11 and 12 of rigid construction, the upper portions of which may be connected by a pan structure 13. The lower ends of the upright members 11 and 12 are tied together by a relatively rigid tie 14, an intermediate portion of which defines a support for a shoe actuating mechanism, generally indicated at 15 and described in detail hereinafter.

A buck structure, generally indicated at 16, includes a shaft 17 which is suitably journaled in

2

the upper portions of the upright members 11 and 12. A bearing 18 secured to the upright member 11 rotatably supports the shaft 17 so that the buck structure 16 may be rotated. It will be understood that the opposite end of the buck structure 16 is also carried by a bearing (not shown) similar to the bearing 18 and fixed to the upper end of the upright member 12. The buck structure includes a plurality of bucks 19 to 22, inclusive, which are of different configuration in order to facilitate the ironing of different pieces such as flatwork and complicated garments, for example, dresses and men's shirts. The buck 19 may be generally rectangular in configuration for the ironing of flatwork and the buck 21 may taper in a manner similar to the end of a conventional ironing board for the ironing of large tubular articles. The buck 22 may be shaped to fit the upper portion of men's shirts, and the buck 20 may be a relatively narrow buck for the single thickness ironing of sleeves. The buck shapes have not been shown in detail as the shapes are well understood to those skilled in the art.

The various bucks 19 to 22, inclusive, may be selectively moved into pressing position by manually rotating the buck structure 16. In order to properly position the selected buck, an indexing mechanism is employed which mechanism includes an index plate 23 secured to one end of the shaft 17 in any well-understood manner. The plate 23 is provided with a plurality of recesses or notches 24 at its outer periphery and corresponding in number to the number of the bucks employed. A latch 25, pivoted as shown at 26 to the casing 10, has one of its ends normally disposed within one of the notches 24 for positioning the buck structure 16. The opposite end of the latch 25 is connected by means of a tension spring 27 to the casing 10 and this spring biases the latch 25 into the position shown in the drawing wherein its upper end is disposed in one of the notches 24.

A rod 28 has a push plate 29 secured to one of its ends and the opposite end of the rod 28 is pivotally connected as shown at 31 to the latch 25. When it is desired to rotate the buck structure 16, the push plate 29 may be depressed for withdrawing the latch 25 from the notch 24, after which the buck structure is manually rotated until the proper buck is in pressing position. The push plate 29 is then released and the parts are returned to the position shown in the drawing by the spring 27. Preferably, the push plate 29 is disposed on the casing 10 where it may be conveniently operated by the leg of the operator.

A conventional shoe 32 cooperates with the buck selected for operation and is moved into and out of pressing engagement therewith by the shoe actuating mechanism 15, as will be described hereinafter. The shoe 32 is provided with a handle 33 on the front edge thereof and is carried by an arm 34, extending rearwardly and downwardly from the shoe 32. The lower end of the arm 34 is provided with a strap 35 fitted around an eccentric 36. In order that the operator may readily arrange the fabrics to be pressed upon the selected buck, the shoe 32 is movable by means of a handle 33 to a position out of registry with the buck as shown in broken lines in Fig. 2. Rearward movement of the shoe 32 is limited by a chain and tension spring assembly, indicated at 37, one end of which is secured to the arm 34, and the other end of which is attached to the frame structure 10 in any well-understood manner. During the movement of the shoe 32 just described it will be understood that the arm 34 and the strap 35 attached thereto pivot about the eccentric 36.

After the fabrics are properly disposed upon the selected buck, the operator draws the shoe 32 into position in registry with the buck by means of the handle 33. The shoe actuating mechanism 15 is then operated in the manner described herein-after and the eccentric 36 is rotated 180° for moving the arm 34 and shoe 32 downwardly into pressing engagement with the buck. At the conclusion of the pressing operation, the mechanism is again operated and the eccentric is again operated 180° for disengaging the shoe 32 from the fabrics on the buck. The shoe is then moved by means of the handle 33 to its position out of registry with the buck in order to permit the operator to remove the pressed garment. The shoe actuating mechanism 15 will now be described.

As best shown in Figs. 4 to 8, inclusive, the shoe actuating mechanism 15 includes a housing 41 which supports an electric motor, shown at 42, the driving shaft 43 of which carries a pinion 44. The latter meshes with a gear 45 which is fixed to a shaft 46, suitably journaled in the housing 41 in any well-understood manner. A worm 47 is carried by the shaft 46 and meshes with the worm wheel 48 which loosely runs upon a shaft 49 which is also suitably journaled in the housing 41. The outer end of the shaft 49 is fixed to the eccentric 36 referred to heretofore.

Arranged on one face of the worm wheel 48, is an annular wall 51 having one or more notches 52 formed therein. A circular disk 53 which is keyed to the shaft 49, as shown at 54, is arranged within the annular wall 51 and includes a recess 55 extending radially to its periphery. Within the recess 55, a dog 56 is slidably arranged and biased outwardly by means of a flat spring 57, one end of which engages the dog 56, as best shown in Fig. 7, and the opposite end 58 of which is secured to the plate 53 within an extension 55a of the recess 55. This construction is best shown in Figs. 7 and 8. The dog 56 carries a pin 59 which operates to move the dog 56 inwardly against the bias of the spring 57 as described hereinafter.

Normally the dog 56 is held inwardly as shown in Fig. 6 so that the worm wheel 48 is free to turn on the shaft 49 during operation of the motor 42. The dog 56 is held inwardly at this time by a cam plate 61, best shown in Figs. 4 and 6, which plate 61 is carried by rods 62, slidably mounted in the housing 41 and biased to the position shown in the drawing by compression springs 63. The cam plate 61 includes two cams 64 and 65 ar-

ranged 180° apart and in planes which are intersected by the pin 59 when the latter is rotated by the shaft 49. In the position of the plate 61, shown in Fig. 6, the pin 59 engages the undersurface of the cam 64 and holds the dog 56 inwardly against the bias of the spring 57.

In order to clutch the rotating worm wheel 48 and the disk 53, the plate 61 is moved to the left, in a manner to be described, sufficiently to move the cam 64 out of engagement with the pin 59 whereupon the spring 57 moves the dog 56 outwardly within one of the recesses 52. A driving connection is, therefore, established between the wall 51 of the rotating worm wheel 48 and the disk 53 so that the shaft 49 and disk 53 will rotate with the worm wheel 48. During downward movement of the pin 59 in the direction of the arrow (Fig. 4) the plate 61 is returned to the position shown in the drawing by the spring 63, as described hereinafter. Accordingly, as the pin 59 approaches its lowermost position, it engages the cam 65 and rides therealong until its total movement approximates 180°. As the pin 59 rides along the cam 65 it moves inwardly of the disk 53 and disconnects the dog 56 from the wall 51 when the pin 59 has been moved 180° from its former position. Rotation of the disk 53 and shaft 49 is, therefore, terminated. The next time the plate 61 is actuated, the cam 65 releases the pin 59 and clutches the dog 56 and wall 51. The disk 53 and shaft 49 are rotated 180° or until the pin 59 is arrested by the cam 64, which operation withdraws the dog 56 from the recess 52 in the wall 51. Accordingly, rotation of the disk 53 and shaft 49 is stopped. The disk 53, shaft 49 and the eccentric 36 are moved 180° each time the plate 61 is actuated, as described. The 180° movement of the eccentric 36 either engages or disengages the shoe 32 and the buck registering there-

with.

The axes of the shafts 49 and 17 are disposed in a line normal to the surface of the buck selected for operation and intersecting the center of said buck in order that substantially all of the force provided by the eccentric is normal to the surface of the buck with no component of the force acting to move the shoe 32 along the buck during engagement of these members. The line of force provided by the eccentric during engagement of the shoe and buck passes through the axis of the shaft 17 so that there is no turning movement effective to rotate the buck structure 16 in its bearings 18.

The cam plate 61 is actuated by the operator at will by a mechanism including a foot treadle 66, pivoted at 67, to the frame 10 and the free end of which is pivoted to a bell crank lever 68. The latter is pivotally carried by the casing 41 and engages a collar 69 fixed to the outer end 60 of the rods 62. When the operator momentarily depresses the foot treadle 66, the rods 62 are moved to the left against the bias of the springs 63 by means of the bell crank lever 68. A 180° movement of the eccentric 36 results, as described heretofore, and the shoe is actuated. It will be understood that the operator depresses the treadle 66 momentarily in actuating the shoe, that is, the treadle 66 is depressed and immediately released. This operation withdraws the cam 64 from the pin 59 and immediately positions the cam 65 in the path of the pin 59 before the shaft 49 and eccentric 36 have completed 180° of movement. If the shoe is disengaged from the buck, as shown, the described actuation of the treadle 66 engages the shoe and buck.

The next actuation of the treadle 66 will disengage the shoe and buck as will be apparent.

In operating the press, the operator sits at the front of the machine where the treadle 66 may be readily actuated by the foot and where the push plate 29 may be moved by the leg or knee of the operator. The switch, controlling energization of the motor 42 and the heating element (not shown) of the shoe 32, may be arranged on the frame 10 in any convenient location such as, for example, on the front side of the upright 12 as shown at 71. The operator collects the flatwork and actuates the flatwork buck 19 to its pressing position, as described. After the pressing of the flatwork is completed, tubular garments may be ironed and the buck 21 employed for this operation. The shirts are pressed on the shirt buck 22 and the sleeves thereof and small tubular garments are pressed on the narrow buck 20.

From the foregoing description, it will be apparent that I have provided an improved operating mechanism for the shoe of a pressing machine wherein the pressure between the shoe and buck is mechanically applied and which mechanism permits actuation of the shoe into and out of registry with the buck. The shoe actuating mechanism may be applied to machines having one or more bucks but is particularly adaptable to a multiple-buck machine of the turret type, as disclosed herein, since the shoe may be moved laterally with respect to the buck sufficiently to permit manual adjustment of the buck structure without danger of burning or other injury to the operator. The multiple-buck structure which I have disclosed may be readily actuated to its selective positions by the operator from a seated position, the control element for positioning the buck structure being conveniently disposed adjacent the leg of the operator.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a laundry press, the combination of a frame, a turret like buck structure having a shaft journaled in the frame and a plurality of bucks circumferentially spaced about said shaft, said buck structure being manually movable to a plurality of positions for selectively disposing the bucks in pressing position, a shoe cooperating with the buck selected for operation and having a rigid unitary supporting bracket fixed at one of its ends to the shoe and extending rearwardly

and downwardly therefrom, an eccentric journaled in the lower end of the shoe-supporting bracket for supporting the bracket and for actuating the shoe into and out of engagement with the selected buck, means including a second shaft for rotating the eccentric in steps of 180° for alternatively moving the shoe into and out of engagement with the selected buck, said first and second shafts having their axes disposed in a plane intersecting substantially the center of the selected buck and normal to the surface thereof, and means for swinging the shoe and its supporting bracket about the eccentric to a position out of registry with the selected buck to facilitate the arrangement of fabrics to be pressed upon said buck.

2. In a laundry press, the combination of a frame, a turret like buck structure journaled in the frame and having a plurality of bucks circumferentially spaced about the axis of the buck structure, said buck structure being manually movable about said axis to a plurality of positions for selectively disposing the bucks in pressing position, a shoe cooperating with the buck selected for operation and having a rigid unitary supporting bracket fixed at one of its ends to the shoe and extending rearwardly and downwardly therefrom, an eccentric journaled in the lower end of the shoe supporting bracket for supporting the bracket and for actuating the shoe into and out of engagement with the selected buck, means including a shaft for moving the eccentric to first and second positions for alternatively actuating the shoe into and out of engagement with the selected buck, said axis of the turret like buck structure and the axis of said shaft being disposed in a plane intersecting substantially the center of the selected buck and generally normal to the surface thereof, and means for swinging the shoe and its supporting bracket about the eccentric to a position out of registry with the selected buck to facilitate the arrangement of fabrics to be pressed upon said buck.

FRANK BRECKENRIDGE.
